(57) **CLAIM**

The ornamental design for a hydrocyclone inlet head, as shown and described.

DESCRIPTION

FIG. 1 is a perspective view of a hydrocyclone inlet head showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a plan view thereof;

FIG. 7 is a bottom view thereof;

FIG. 8 is a cross-sectional view thereof taken along the line 8-8 shown in FIG. 6;

FIG. 9 is a cross-sectional view thereof taken along the line 8-8 shown in FIG. 6; and,

FIG. 10 is a cross-sectional view thereof taken along the line 8-8 shown in FIG. 6.

The thin broken lines shown in the drawings illustrate portions of the hydrocyclone inlet head that are unclaimed environmental subject matter.

The thick broken lines shown in FIGS. 1, 2, and 6 depict the boundaries of the claimed design and form no part thereof.
